COOLING SYSTEM FOR FOUNDRY MOLDS

Erwin Bührer, Schaffhausen, Switzerland, assignor to Georg Fischer Aktiengesellschaft, Schaffhausen, Switzerland

Filed Aug. 28, 1957, Ser. No. 680,797

Claims priority, application Switzerland Aug. 28, 1956

4 Claims. (Cl. 198—31)

The present invention relates to a transporting system for the handling of articles, and more particularly, to a system for transporting and transferring foundry molds from and to conveyors or like support means.

It is well known that the molds employed in metal working foundries, after the casting operation has been performed on them, are permitted to travel on a conveyor or track along a predetermined path and for a desired period of time, in order to permit the cooling down of the casting molds to a state where the casting may be unpacked without any risk or danger of damaging the casting.

It has been found desirable to unpack each casting mold as rapidly as possible in order to retain the maximum quantity of the admixtures in the molding sand, namely the coal dust and cementing clay. Since thin-walled castings may be unpacked much sooner after the casting operation than thick-walled castings, due to their increased cooling rates or solidification velocity, it is therefore desirable to provide some means of conveying the thin-walled castings from the transporting system to the unpacking station as quickly as possible in order that they may be unpacked.

As a result of the different cooling periods required for the various size castings contained in the molds and which are carried on a feeding or supply conveyor, a number of solutions has been proposed in regard to the removal or storage of the casting molds which require the greater cooling time.

One attempted solution to this problem was that the casting molds which require longer cooling periods were laterally shifted from the main supply conveyor and piled onto another conveyor track and thence to an unpacking station.

Another known solution to this problem provides for a vertical storage rack, wherein are placed the casting molds which require longer cooling periods, their transportation from and to the conveying track being performed by an elevating mechanism.

These various solutions to the aforementioned problem have the disadvantage that the transferring systems are comparatively complicated and will not permit the use of a completely automatic conveying system since certain steps during the transporting of the molds from the pouring station to the unpacking station must be achieved manually.

It is therefore an object of this invention to provide means effectuating the transfer of articles having different cooling rates between the working stations of a foundry in a highly efficacious and reliable manner, without necessitating the use of auxiliary storage means as was heretofore known.

It is another object of this invention to provide means permitting the automatic transfer of castings having different cooling rates between the various operating stations.

It is a further object of this invention to provide means contributing to a positive control of the movement of the molds between the desired operating stations.

An ancillary object of the invention is the provision of means permitting the transfer of articles between working stations of a foundry in accordance with the movement of a feeding member.

2

The present invention provides a foundry with a superior transferring and transporting system capable of highly efficient operation, which system is extremely compact in its construction.

5 Therefore, the present invention utilizes a plurality of cooling conveyors which are interposed between a feeding and a delivery conveyor, the number of said cooling conveyors being a function of the various existing cooling periods. The molds which are carried by the feeding conveyor are arranged in a certain sequence and periodically fed onto the delivery conveyor from the cooling conveyor in accordance with the respective cooling rates of the castings, so that each cooling conveyor only contains those castings having the same cooling rate. The feeding of the castings from the cooling conveyor to the delivery conveyor is achieved by means of a lifting device. Prior to the automatic operation of the device being commenced, different numbers of molds or empty flasks are placed on each of the respective cooling conveyors. Thus, when the automatic operation begins, the number of molds which at any time is transferred from the cooling conveyor to the lifting device may be the same as the number of molds transferred from the feeding conveyor to the cooling conveyors.

10 25 The above and other objects of the invention will become further apparent from the following detailed description, reference being made to the accompanying drawings showing preferred embodiments of the invention.

30 Fig. 1 shows schematically a plan view of a first embodiment of the invention;

Fig. 2 is an enlarged sectional elevational view showing details of the lifting device seen in Fig. 1;

Fig. 3 shows schematically a plan view of another embodiment of the invention; and

Fig. 4 shows details of the cooling conveyor employed in Fig. 3.

Referring now to the drawings, and more particularly to Figs. 1 and 2, the transporting system comprises a feeding or supply conveyor 1 which continuously feeds the casting molds 2 which have previously been filled with a molten metal, as for example, iron, and are moving in the direction of arrow 3. Disposed substantially perpendicular to the direction of movement of the casting molds 2 on the feeding conveyor are feed rods or push-off devices 4, consisting of a piston and cylinder arrangement, wherein the piston is actuated by means of compressed air or any other suitable fluid medium. A pressure valve 47 is located adjacent to the feeding conveyor 1 and one of the push-off devices 4. The pressure valve receives a supply of compressed air from a source (not shown) and subsequently, feeds said compressed air to the push-off devices by means of conduits 48 which are disposed between the push-off devices 4 and the pressure valve 47. The withdrawal or retraction of the pistons of the push-off devices may, for example, be effectuated by return springs or any other suitable means. The supply conveyor 1 is provided with stop dog or trigger cam means 45, 46, which are spaced a predetermined distance from each other on the supply conveyor.

55 60 Spaced from the supply conveyor 1 and lying in a plane which is substantially parallel to said supply conveyor is a delivery or discharge conveyor 13 which leads to an unpacking station (not shown in the drawing). A number of roller conveyors 5, 6, 7, 8 provided with roller means 9 are interposed between the supply conveyor 1 and the discharge conveyor 13.

65 70 The number of such roller or cooling conveyors is directly proportional and equal to the number of different cooling rates of the castings. Each of the cooling conveyors is adjustable so that its position or angle of inclination may be altered.

These cooling conveyors are further provided with stop members or holding devices 23, the construction of which is already known, said stop members may preferably be located at the respective ends of the cooling conveyors and remote from the feeding or supply conveyor 1. The stop members are actuated by means of compressed air delivered from the pressure valve 47 through conduit 49. Thus, as the trigger cam 45 passes the pressure valve 47, the latter is opened and feeds a supply of compressed air to the push-off devices 4 by means of conduit 48 and to the stop members 23 by means of conduit 49 in order to displace the casting molds from the supply conveyor onto the cooling conveyors. The stop members which have been opened permit the casting molds to be transferred from the cooling conveyors onto the lifting conveyor 10; the construction of the latter will be described shortly. Further movement of the supply conveyor carries trigger cam 46 past the valve 47, whereby the latter is deactivated, cutting off the supply of compressed air to both the push-off devices 4 and the holding devices 23 in order to retract the pistons by means of the springs and to close the holding devices, respectively.

The aforementioned lifting conveyor 10 is located adjacent the holding devices 23 and is arranged in alignment with the delivery conveyor 13. The push-off devices 4 displace the casting molds 2 traveling on supply conveyor 1 onto the cooling conveyors 5-8, so that the molds move towards the lifting conveyor 10 (in the direction of arrow 34); either due to their own weight or by adjusting the angle of inclination of said cooling conveyors. The lifting conveyor 10 receives the casting molds from the cooling conveyors 5-8 and imparts a movement to said casting molds in the direction of movement of the delivery conveyor 13, namely, in the direction of arrow 36.

The lifting conveyor or stand 10, shown in an enlarged scale and in section in Fig. 2, consists of a frame 14 made of steel or the like. A plurality of transverse roller tracks 11 in combination with rollers 12 is carried by the frame, rollers 12 supporting chain wheels 18 which are laterally disposed on said rollers. A motor 16 drives, by means of a sprocket or flanged gear 16a, a chain 17 which is in engagement with the chain wheels 18 in order to rotate the rollers 12, the transverse rollers being spaced from each other.

A hydraulically actuated cylinder 19 is located adjacent the lifting conveyor 10 and slidably supports a piston rod 21 which is adapted to move along its longitudinal axis. A plurality of bell cranks or levers 20 are pivotally secured to the frame 14 by means of their shorter arm. The longer arm of said bell cranks is connected to the piston rod 21 so that upon longitudinal movement of said piston rod in one direction the lifting conveyor 10 raises the casting molds which are supported on the rollers 12, whereas movement of said piston rod in the opposite direction lowers said lifting conveyor, the bell cranks pivoting about the axis 22. When the lifting stand is in its raised position, as seen in Fig. 2, the motor 16 is actuated in order to impart a rotational movement to the rollers 12, thereby moving the casting molds onto the delivery conveyor 13.

The operation of the transfer system shown in Figs. 1 and 2 is as follows:

A supply of molds which have been arranged in a predetermined sequence on the supply conveyor and have been previously filled with a molten metal is carried by the supply conveyor 1 from the pouring station towards the push-off devices 4. The trigger cams 45 and 46, which have previously been spaced at the desired location along the supply conveyor move towards the pressure valve 47. Prior to the automatic operation of the device being commenced, different numbers of molds or empty flasks are placed for preloading on each of the respective cooling conveyors.

Upon reaching the pressure valve, trigger cam 45 actuates said valve so that the push-off devices move a group

of casting molds, for example four casting molds as seen in Fig. 1, which have arrived in front of the roller or cooling conveyors 5-8 onto the latter, the casting molds moving down towards the locking or stop devices 23 or to the last mold located on the respective cooling conveyors, either due to their own weight or by tilting the roller conveyor. Each roller or cooling conveyor is supplied with casting molds having the same cooling rate. The trigger cam 45 simultaneously actuates the holding devices 23 so that said holding devices are opened to permit movement of a group of four casting molds onto the lifting stand, the latter being in position to receive said molds. Continued movement of the supply conveyor causes trigger cam 46 to deactivate valve 47 so that the push-off devices 4 are retracted and the holding devices 23 are closed. The lifting conveyor 10 receives the casting molds from the cooling conveyor at the same time that a new group of casting molds is pushed onto the cooling conveyors. The lifting conveyor is then hoisted by means of the pressure cylinder 19, and the motor 16 is actuated in order to drive the rollers 12, whereby the casting molds are conveyed onto the discharge conveyor 13, which leads to the unpacking station. This operation is repeated as each trigger cam 45 and 46 reaches the pressure valve 47.

Thus it will be readily apparent that the number of molds, which at any time is transferred from the cooling conveyor to the lifting device may be the same as the number of molds transferred at the same time from the feeding conveyor to the cooling conveyor. As a result of placing staples of molds or different numbers of molds or empty flasks for the purpose of preloading onto the respective cooling conveyors prior to the automatic operation of the device, upon actuation of the device four molds (see Fig. 1) are transferred from the feeding device to the cooling conveyor, and four of the previous flasks will at the same time be transferred to the lifting device from the cooling conveyor. The casting molds which actually require cooling will remain on one specific conveyor during a time which is required to remove therefrom the empty flasks previously placed thereon. Since this number of empty flasks or molds is different for each one of the conveyors, the cooling time provided by each one of the conveyors for the casting molds is different.

It is, of course, to be understood that it is possible to transfer at one and the same time less than four molds.

The spacing of the trigger cams 45, 46 along the conveyor can be altered so that any desired number of push-off devices and cooling conveyors can be used. It is desired to have as many cooling conveyors as there are various cooling rates, although it is possible to have an excess number of cooling conveyors so that some of the cooling conveyors carry molds having the same cooling rate.

In the embodiment shown in Fig. 3, the supply conveyor 25 is disposed adjacent a plurality of substantially U-shaped roller or cooling conveyors 28-31. Push-off devices 26 similar to those shown in Fig. 1 shift the casting molds 27 as they move past the push-off devices 26 onto the desired cooling conveyors 28, 29, 30, 31. The pressure valve, the trigger cams and the respective conduits leading to the push-off devices, and the holding devices, as shown in Fig. 1, have been omitted from Fig. 3 for the sake of clarity.

A lifting roller conveyor 32 which is similar in construction to the lifting device discussed in Fig. 2 receives the casting molds from the roller conveyors and deposits them onto the discharge conveyor track 33.

The transfer system shown in Fig. 3 differs from that shown in Fig. 1 insofar as each of the roller conveyors 28-31 upon which the cooling of the molds is effectuated has two bends or deflections of approximately 90 degrees.

The arrangement of these roller conveyors in this manner permits the use of conveyors which have different lengths, thereby affording more space for the storage of

the molds during the cooling operation, and especially those molds which require the greater cooling time.

Fig. 4 shows a portion of a cooling conveyor shown in Fig. 3 and how the deflections of 90° can be obtained in actual practice. A group of rollers 40 lying in a common plane and defining a straight portion of the roller conveyor 31 are inclined in order that casting molds 2, shown in dotted lines in Fig. 4, will move thereon due to their own weight and to the slight inclination of the rollers 40. In front of the bend or deflection there is arranged a group of rollers 41 which are driven by a chain 42 by means of a suitable motor or prime mover (not shown). This group of rollers 41 is arranged so as to have a small rise or upward inclination of about 0.2%. The casting molds 2 are moved from the rollers 41 to the group of rollers 43, which form the bend or deflection in the conveyor, the upper edges of these rollers 43 lying in a horizontal plane. The casting molds upon passing over this group of rollers 43 are turned approximately 90° from their initial direction of travel, this group of rollers being also driven by a motor or prime mover.

Disposed adjacent the last roller of this roller group 43 and at the termination point of the bend is a group of rollers 44 which are similar to rollers 40 and form the straight portion of the cooling conveyor, said rollers 44 being inclined in a downward direction to facilitate movement of the casting molds 2 towards the other 90° deflection which is similar in construction to the one previously discussed. At the termination of the deflection and adjacent roller 45a there is suitably installed and located a switch (not shown) which is actuated by the molds 2 in order to disconnect both of the driving motors or prime movers for the roller groups 41 and 43. The actuation of said switch occurs when the cooling conveyor including the roller group 44 cannot receive molds any longer. As a result of stopping the motors which drive the roller groups 41 and 43, it is possible to prevent an agglomeration or collecting of the molds at the bend of the cooling conveyor, so that the movement of the molds on the cooling conveyor will not be hampered or interrupted.

It is also possible to operate a cooling track, as shown in Fig. 3, with only one or two roller conveyors and to keep in readiness one or more roller conveyors which will be used as supplemental cooling conveyors when a pattern modification requires a cooling period for the newly formed molds different from that which has hitherto been run.

It is also to be noted that in the embodiments of Figs. 3 and 4 it is possible to selectively actuate the respective holding devices in order to selectively transfer the casting molds from the respective cooling conveyors to the lifting device.

The transferring system of this invention can also be arranged in such a manner that one more cooling conveyor can be installed in excess of the number of different cooling periods required for the molds. This supplemental roller conveyor should be installed when there is a reduction in the cooling period of the molds.

Thus a principal advantage of the present invention is readily apparent, namely, a smooth course of automatically and mechanically conveying casting molds between the pouring and shake-out stations of a foundry, wherein said casting molds have different cooling rates. The transferring system of the present invention, and particularly the cooling conveyors require less space than the heretofore known systems used with molds having different cooling periods.

Various changes and modifications may be made without departing from the spirit and scope of the present invention and it is intended that such obvious changes and modifications be embraced by the annexed claims.

Having thus described the invention, what is claimed as new and desired to be secured by Letters Patent, is:

1. A system for substantially uniformly cooling foundry

molds having a plurality of different cooling rates; comprising a feeding conveyor for carrying and moving molds in a predetermined path, a delivery conveyor spaced from said feeding conveyor, a plurality of cooling conveyors providing communication between said feeding and delivery conveyors, push-off means disposed adjacent said feeding conveyor for effectuating movement of molds onto the cooling conveyors, stop means located between said cooling conveyors and said delivery conveyor and coordinated with said push-off means to permit movement of molds already loaded onto said cooling conveyors from the latter to the delivery conveyor when the previously loaded molds have been cooled, and control means in registry with said push-off means and said stop means to periodically actuate and deactivate said push-off means and said stop means in accordance with the movement of said feeding conveyor, said cooling conveyors extending substantially in U-shaped formation, so that each cooling conveyor has a different overall length for storage of molds.

2. A system according to claim 1, said substantially U-shaped cooling conveyors having two 90° deflections and being provided with rollers, drive means for driving said rollers which are disposed adjacent said 90° deflections, and switch means located adjacent said driven rollers to deactivate said drive means when said cooling conveyors are carrying a predetermined number of molds, in order to prevent overcrowding of molds on said cooling conveyors.

3. A system for substantially uniformly cooling foundry molds having a plurality of different cooling rates; comprising a feeding conveyor, a delivery conveyor spaced from said feeding conveyor, a plurality of cooling conveyors having respective first and second end portions, said cooling conveyors providing a path of movement for molds from said feeding conveyor to said delivery conveyor and being preloaded with a predetermined number of molds respectively, push-off means disposed adjacent said first end portion of each of said cooling conveyors for causing movement of molds from the feeding conveyor onto said cooling conveyors, holding means located adjacent said second end portion of each of said cooling conveyors, a lifting conveyor located adjacent said holding means, and control means in registry with said push-off means and said holding means, to thereby permit displacement of molds from said feeding conveyor onto predetermined cooling conveyors in accordance with the respective cooling rates and with said predetermined number of preloaded molds and from the said cooling conveyors onto said lifting conveyor upon actuation of said push-off means and said holding means by said control means.

4. The method for substantially uniformly cooling foundry molds of various cooling rates; comprising the steps of preloading respective cooling conveyor means with molds according to the duration of cooling, placing heated molds on a feeding conveyor, transferring said heated molds from said feeding conveyor to said respective cooling conveyor means corresponding to their rates of cooling, subjecting the molds on said respective preloaded cooling conveyor means to cooling action for respective predetermined periods of time, and simultaneously transferring a single mold from the respective cooling conveyor means to a delivery conveyor as a mold is being fed to the respective cooling conveyor means.
